UNITED STATES PATENT OFFICE.

ORRIN W. BRICKER, OF CLEVELAND, OHIO, ASSIGNOR TO UNA WELDING & BONDING COMPANY, OF CLEVELAND, OHIO, A CORPORATION OF OHIO.

STARTING SWITCH.

Application filed March 1, 1926. Serial No. 91,639.

My invention is an improvement in starting switches and is adapted more particularly for use in starting dynamotors used in the electric welding of rail joints and the like.

5 An important object of my invention is the construction of a starting switch of the above named character which permits of a sufficient lapse of time between each successive step thereof so that the motor will have an opportunity to speed up before the next step is thrown in.

Another important object of my invention is the construction of a starting switch having a plurality of contacting arms adapted to 15 be operated in successive steps, and having automatic means for releasing the arms.

Another object of my invention is to construct a switch of the above character having both manual and automatic releasing means.

20 Other objects and advantages will become apparent as the description of my invention progresses, reference being had to the accompanying drawings forming a part of this specification and in which like numerals are 25 used to designate like parts throughout.

In the drawings:

Fig. 1 is a plan view of the switch shown mounted on an insulating panel;

Fig. 2 is a side elevation of the main shaft 30 and assembly;

Fig. 3 is a section taken on line 3—3 of Fig. 1, showing the pawl and ratchet construction on the left hand end of the main shaft;

Fig. 4 is a section taken on line 4—4 of Fig. 1;

Fig. 5 is a detail view of one of the ratchets;

Fig. 6 is a section taken on line 6—6 of Fig. 1;

Fig. 7 is a slightly enlarged end view on line 7—7 of Fig. 1;

Fig. 8 is a detail of a second ratchet device and,

Fig. 9 is a diagrammatic view of the wiring of the switch.

In the drawings, the entire switch assembly is mounted on an insulated panel 4 and includes a series of contacting arms, means for operating the arms, and contact blocks which are engaged by the contact arms. A cover 5 is provided for the switch mechanism and is shown in Fig. 1 partly broken away.

I provide a supporting frame 6 which carries end supporting brackets 7 and 8. Inter-

mediate these brackets and along the base of the frame are a series of supporting arms 9 extending downwardly in Figs. 1 and 3 which are provided with aligned openings to carry a supporting shaft 10. This shaft is adapted 60 to carry the contact arms 11, 12 and 13, as shown, each arm being rotatably mounted between a pair of the supporting arms 9. On the ends of the shaft I provide collars to prevent any great amount of longitudinal movement of the shaft 10.

The supporting brackets 7 and 8 are in alignment and are provided with bearing surfaces 16 and 17, respectively. Bracket 7 carries a resilient stop member 18 which will be 70 described more fully as the specification proceeds.

A shaft 19 is mounted to rotate in either direction upon the bearings 16 and 17 and is held in place by bearing blocks 20 and 21 75 which provide the upper bearing surfaces for the shaft. The shaft is provided with tension means for normally tending to rotate the shaft in one direction, which consists of a coil spring 22 coiled about one end of the shaft 19 80 and having one of its ends embedded in a collar 23 secured to the end of the shaft and its other end embedded in the top bearing block 20. The bearing block 20 is slotted as at 24 and carries therein a pivoted pawl 25 having 85 a handle 26 of insulating material. Keyed to the shaft 19 is a ratchet member 27 shown in detail in Fig. 5. This ratchet rotates with the shaft 19 and abuts the stop 18 when the notches of the ratchet are engaged by the 90 pawl tooth 28 carried by the pawl 25. Referring to Fig. 5, it will be seen that this ratchet is provided with two notches 29 and 30 and a cam surface 31. The operation of this ratchet will be described presently. It 95 will be noted that the outer side face of this ratchet abuts the inner side walls of bracket 7 and bearing block 20 serving to prevent longitudinal displacement of shaft 19.

At intervals along shaft 19, I have shown 100 cams 32, 33 and 34 keyed to rotate with the shaft and adapted to engage rollers 35, 36 and 37, respectively, carried by arms 11, 12 and 13, respectively, when the shaft 19 is rotated.

A collar 38 fixed to the shaft 19 maintains the shaft against longitudinal movement to the right in Fig. 1 by abutting the side of bearing block 8.

A second pawl and ratchet device is mount- 110

ed on the right hand end of shaft 19 Fig. 1 and consists of a ratchet 39 Fig. 4 fixed to the shaft and a freely movable pawl carrying cage 40 enclosing said ratchet and shaft end. 5 A freely movable pawl 41 is mounted within the cage so that it will contact with the ratchet 39. The cage is also provided with an outwardly extending projection 42, which seats a small coil spring 43, and carries pawl 10 44 having an insulated operating handle 45. The pawl 44 is adapted to engage the teeth of the ratchet 39 shown in detail in Fig. 4 under compression of the spring 43.

15 A disc 46 of insulating material and a second smaller, but thicker disc 47 are secured to the cage 40 by screws. This second disc carries an operating arm 48 having an insulated handle 49 for rotating cage 40 and the pawls 41 and 44 about ratchet 39. A 20 pivoted armature 50 is suspended below the handle for engagement with the poles 51 of an electromagnet and when current is applied to the magnet and when the armature is in contact with the poles, the armature and handle will be held thereby, until the electromagnet is de-energized. 25

Secured to the base of bracket 8 is a pawl stop and trip device consisting of a substantially vertically extending arm 52 having a 30 head 53 to limit the movement of the operating handle 45, when the same is moved in that direction. It will be noted that the upper edge of a stop plate 54 is beveled as at 54' and that the plate is removably attached 35 to the stop device by a screw 55. The purpose of this stop plate will be hereinafter more fully described.

Referring now to the contact arms 11, 12 and 13, it will be observed that they are substantially alike in construction. Each is provided with an opening through which the shaft 10 passes and upon which the arms rock. The contact arms are provided with lower rollers 35, 36 and 37 and upper rollers 45 35', 36' and 37' carried by supports 57, 58 and 59, respectively, which are adapted to contact with the cams 32, 33 and 34, respectively, when shaft 19 is rocked.

The outer ends of the contact arms are 50 each provided with an upwardly extending projection adapted to seat one end of the springs 63, 64 and 65, respectively. The opposite ends of the springs engage pivoted contact pieces 66, 67 and 68, respectively, and 55 normally force them forwardly.

I have provided contact blocks which consist essentially of copper contact members 72 bent upwardly from the panel and partially housing carbon blocks 73. The carbon 60 blocks abut the outwardly projecting portion of the copper pieces but their upper contacting surface is short of the upper contacting surface of the members 72. It will be seen, therefore, that as the arms 11, 12 and 13 65 are rocked to bring the contacts 66, 67 and 68,

respectively, into contact with the respective blocks, the contacts will first engage the carbon block and when the respective arms are rocked to complete contact position the contacts will engage the copper members. This 70 method of making the initial contact between copper and carbon and then finally between two copper members results in a more perfect electrical contact and less arcing. Of course when the contact is broken, the final 75 step in the break occurs between copper and carbon.

The tendency to arc is greater at the contact 66 on arm 11 than at the other contacts and to help overcome this condition I have 80 provided blowout coils 74 and 75 each in close proximity to the contacts and creating a strong magnetic field directly across the path of the arc. Such a magnetic field has a 85 quenching effect on the arc. These coils are protected from direct exposure to the arc by sections of refractory material as shown at 76.

I have also provided sections of refractory 90 material on the opposite sides of contact 67, as shown at 77, to prevent any tendency of a spreading arc at this point although the tendency to arc at this point is somewhat reduced.

Each of the arms 11, 12 and 13 is provided 95 with connector strips 78 to provide a more positive connection from the contacts 66, 67 and 68 respectively, to suitable binding posts on the rear of the panel.

I will now describe the operation of the de- 100 vice through the various steps.

The switch being open, contact arms 11, 12 and 13 are normally held up and out of contact position by rollers 35', 36' and 37' coming into contact with cams 32, 33 and 34 respectively.

When it is desired to close the switch to operate the dynamotor to which it is connected, the operator grasps handle 49 with the right hand and handle 26 with his left. A 110 forward motion is imparted to lever 48 and the discs 46 and 47 are rotated carrying cage 40, pawl 44 and handle 45 and causing the spring-pressed pawl 44 to ride over the ratchet surface to engage tooth A for the 115 first step. As the handle 49 is moved forwardly several actions take place simultaneously, namely, pawl 44 engages tooth A of the ratchet 39 which is keyed to shaft 19, and turns shaft 19 against the tension of spring 22. As the ratchet and shaft revolve the free 120 pawl 41 will engage the cam section 80 of the ratchet and as the ratchet and free pawl assume an advanced position during the first step, the pawl 41 will be forced to abut the 125 stop 54 thus limiting the movement of the shaft and handle. When the shaft and handle 49 have been thus advanced during the first step, the ratchet 27 also has been advanced so that its first notch 29 is engaged 130

by the pawl 28. The operator prevents any backward rotation of shaft 19 by maintaining sufficient pressure on the handle 26 by the left hand. While the handle 49 is being brought back to its normal position to begin the second step, the operator must apply pressure to handle 26 to prevent backward turning of shaft 19. During the first step it will be observed that as shaft 19 is turned cam 32 is rotated partly in contact with roller 35. As the cam leaves this roller it engages roller 35' and forces arm 11 downwardly to make the contact.

The second step is similar to the first except that ratchets 27 and 39 are advanced a step as shown in Figs. 3 and 7 by dotted lines, and the pawls 28 and 44 now engage the notch 30 and tooth B respectively. During the second step the cam 33 disengages roller 36 and 20 engages roller 36' to move arm 12 into contact position. It will be noted that further movement of cams 32 and 33 during the three steps merely serve to lock arms 11 and 12 in contact position.

25 After operating handle 49 has been returned to normal position for the third step and the operator has securely held the shaft against rotation by means of handle 26, the apparatus is ready for the final step.

30 As the handle 49 is again moved forwardly pawl 44 engages tooth C of the ratchet and moves the ratchet forward. During this latter motion the free pawl 41 will not engage the cam surface 80 of the ratchet, but will 35 fully seat itself within cage 40 in order to pass over the stop 54. This permits the handle 49 to be depressed forwardly until the armature 50 is carried thereby comes into contact with the poles of the electromagnet as 40 shown at 51. As in the previous steps described, cam 34 disengages roller 37 and engages roller 37', forcing arm 13 into contact position. It is no longer necessary to depress handle 26 since the switch is now entirely closed and current is passing through 45 the magnet which securely holds the armature and, consequently, the operating handle 49 in place.

When it is desired to release the switch 50 arms from their contact positions, it is only necessary to exert a forward pressure upon handle 45 which releases pawl 44 from engagement with tooth C of the ratchet 39, and causes shaft 19 to return to normal position 55 by virtue of spring 22 which, during the closing operation, has been coiled under tension.

Likewise, if for any reason current should cease to energize the electro-magnet, the 60 armature 50 would be released returning shaft 19 to normal position, since manual pressure has been released from the pawl 28.

In Figure 9 I have illustrated diagrammatically the wiring of the switch only to the

points where connections are made at the base 65 terminals of the switch.

It is to be understood that various changes may be made in the construction described without departing from the spirit of the invention, or the scope of the subjoined claims. 70

I claim—

1. In a starting switch for dynamotors, a base, a multiplicity of contact arms pivotally mounted thereon, contact blocks cooperating with said contact arms, and means for causing 75 said arms to engage said contact blocks in step by step relation, said means including a shaft, cams carried by said shaft to engage and rock said arms and ratchet wheels carried at the extremities of the shaft to rotate therewith, 80 pawl devices to engage the ratchets, operating handles for said pawls, and means to limit the rotation of said shaft during some of the contacting steps.

2. In a starting switch for dynamotors, a 85 base, a multiplicity of contact arms pivotally mounted thereon, contact blocks cooperating with said contact arms, and means for causing said arms to engage said contact blocks in step by step relation, said means including a shaft, cams carried by said shaft to engage and rock said arms and ratchet wheels carried at the extremities of the shaft to rotate therewith, 90 pawl devices to engage the ratchets, operating handles for said pawls, and means to limit the rotation of said shaft during all but the last step.

3. In a starting switch for dynamotors, a base, a multiplicity of contact arms pivotally mounted thereon, contact blocks cooperating 100 with said contact arms, and means for causing said arms to engage said contact blocks in step by step relation, said means including a shaft, cams carried by said shaft to engage and rock said arms and ratchet wheels carried at the extremities of the shaft to rotate therewith, 105 pawl devices to engage the ratchets, operating handles for said pawls, and means to limit the rotation of said shaft, including an auxiliary pawl movable with one of said other 110 pawls.

4. In a starting switch for dynamotors, a base, a multiplicity of contact arms pivotally mounted thereon, contact blocks cooperating with said contact arms, and means for causing 115 said arms to engage said contact blocks in step by step relation, said means including a shaft, cams carried by said shaft to engage and rock said arms and ratchet wheels carried at the extremities of the shaft to rotate therewith, 120 pawl devices to engage the ratchets, operating handles for said pawls, and means to limit the rotation of said shaft, including an auxiliary pawl movable with one of said other pawls, 125 said auxiliary pawl being inoperative during the last of the step by step movements.

5. In a device of the class described, a base, a multiplicity of contact arms mounted there-

on, contact blocks cooperating with the arms, said arms being dished near the end thereof, rollers carried by said arms on opposite sides of the dished portions, a shaft passing transversely of the arms and approximately centrally of the dished portion, said shaft carrying cams thereon opposite each arm to contact with said rollers, and means for rotating the shaft in step by step fashion, whereby the 10 cams will first contact with the rear arm rollers and then with the centrally disposed rollers to rock the respective arms in contact position.

6. In a device of the class described, a base, 15 a multiplicity of contact arms mounted thereon, contact blocks cooperating with the arms, said arms being dished near the end thereof, rollers carried by said arms on opposite sides of the dished portions, a shaft passing transversely of the arms and approximately centrally of the dished portion, said shaft carrying cams thereon opposite each arm to contact with said rollers, and means for rotating the shaft in step by step fashion, whereby the 20 cams will first contact with the rear arm rollers and then with the centrally disposed rollers to rock the respective arms in contact position, and means for maintaining the shaft in advanced position.

25 7. In a device of the class described, a base, a multiplicity of contact arms mounted thereon, contact blocks cooperating with the arms,

said arms being dished near the end thereof, rollers carried by said arms on opposite sides of the dished portions, a shaft passing transversely of the arms and approximately centrally of the dished portion, said shaft carrying cams thereon opposite each arm to contact with said rollers, and means for rotating the shaft in step by step fashion, whereby the 30 cams will first contact with the rear arm rollers and then with the centrally disposed rollers to rock the respective arms in contact position, and means for maintaining the shaft in advanced position, and means for releasing the shaft upon disruption of the circuit which has been closed by the switch.

8. In a starting switch for dynamotors, a base, a multiplicity of contact arms pivotally mounted thereon, contact blocks cooperating with said contact arms, and means for causing said arms to engage said contact blocks in step by step relation, said means including a shaft, cams carried by the shaft to engage and rock said arms and ratchet wheels carried at the 50 extremities of the shaft to rotate therewith, pawl devices to engage the ratchets, operating handles for the pawls and means to limit the rotation of said shaft during all but one of the said steps.

60 In testimony whereof I hereunto affix my signature this 20th day of February, 1926.

ORRIN W. BRICKER.
